ABSTRACT OF THE DISCLOSURE

A wall bracket specially designed for providing cantilever support to a restaurant tabletop, in an application in which said table top must be wall mounted with precise leveling as well as vertical and horizontal alignment, regardless of imperfections in the structure to which the bracket is mounted, said bracket being a right angle structure with the vertical member in the form of a vertically extended frame comprised of upper and lower vertical plates, connected by a pair of vertically disposed side members; said bracket is attached to mounting studs projecting from the wall, usually two per bracket, by means of an outboard plate on each of said mounting studs, said plate overlapping said side members; alignment and leveling to precise vertical and horizontal spacing, despite substantial departure of both wall and mounting studs from proper plane and location, is achieved by aligning said frame, and applying shims between said upper and lower plates prior to tightening said outboard plates into tight holding position.

This invention relates generally to wall brackets of heavy welded steel structure or the like, used for mounting a table or similar platform to a wall surface by means of mounting studs projecting from said wall surface; more particularly, the wall bracket of the present invention has a vertically extended portion for seating against the wall, said vertically extended portion being in the form of a frame with upper and lower vertical plates, and vertically extended side members, which frame can be positioned in proper alignment despite substantial misalignment of the mounting studs, and may be brought to a suitable level and suitable normal projection from the wall by means of shims between said upper and lower plates and said wall, by virtue of attachment by separate outboard plates received on said mounting studs, which permit adjustment of said bracket into proper position prior to tightening of nuts or other fastening means on said mounting studs.

The present invention is designed specially for problems of wall mounting of tables encountered in restaurant construction. It may have other applications also, but the description of the invention and of its special advantages will be made with reference to the special purpose for which it has been found uniquely suited.

Wall-mounting of tables has been adopted as perhaps the most commonly used type of table in any building specially constructed for use as a restaurant. Floor space is conserved, and floor cleaning is much easier and more effective. It is the universal practice to support the table top on a strong and rigid cantilever wall bracket constructed of welded steel, which is, in turn, bolted to the wall by means of two threaded bolts which have been installed in the wall during construction. Typically, the wall is concrete block or brick masonry, or reinforced concrete, since most building codes require fireproof construction for restaurants. The mounting studs are simply large size lag bolts which have been imbedded in the masonry or concrete during the wall construction. The contractor's drawings require, and the contractor's inspectors insure within some degree of tolerance, that

2

the bolts are installed in the wall at approximately the location desired, and also, that the surface of the wall upon which the bracket is to be mounted is fairly close to a vertical plane surface.

Unfortunately, it has proven extremely difficult, costly, and sometimes impossible at any price, to provide that the mounting studs are precisely located, and also that the wall surface is a true plane extending the entire length of the large room. As a result, when the tables and brackets are mounted, the observer is dismayed to perceive, in most cases, that there are a few inches deviation in horizontal spacing between successive tables, so that the booth seating arrangements have to be custom tailored to accommodate the departure of the mounting studs from correct horizontal spacing. Moreover, the tabletops are at first all askew and awry. The two mounting bolts for brackets are supposed to be in a perfect vertical line for each bracket but as one views a row of these wall mounted tables when first installed, prior to any adjustment, each table in the row is tilted in a different right or left angle, and slight deviations of the wall from a vertical plane produce intolerable down tilt or up tilt of the table in the direction of projection from the wall. Heretofore, there has not been available any bracket with sufficient adjustability on the wall to be properly positioned despite the customary and tolerated departures from alignment of the mounting studs, and departures from the vertical plane of the wall surface. Adjustments have had to be made by skilled craftsmen spending substantial time on the placement of the tabletop on the bracket.

It is not necessarily the purpose of the present invention to avoid all adjustment of the tabletop on the horizontally projecting part of the wall bracket, but to provide a bracket which may be brought so closely to alignment at the wall that such tabletop adjustment will be unnecessary in many cases and at a minimum in the others.

By using the present bracket, custom tailoring of the booth seats may be practically eliminated, since despite misalignment of the mounting studs, a series of restaurant tables can be mounted at the precise spacing required by the booth seats.

In various adjustable and movable table mounting brackets known in the past, a substantial amount of skilled labor was required for installation, and the brackets once installed, could not be salvaged in the event that it was desired to discontinue use of the building as a restaurant, and move the fixtures to another location.

With the bracket of the present invention, wall mounted tables can be installed on mounting studs which are arranged in a pattern which has become practically standard in restaurant construction, and which were not specially installed for accommodation of the present invention.

The foregoing and other objects and advantages are accomplished in the present invention by means best explained by a description of one specific embodiment, set forth hereinafter and illustrated in the accompanying drawings in which:

FIG. 1 is a perspective view of a wall bracket constructed according to the present invention, but shown prior to mounting on the wall;

FIG. 1a illustrates an outboard plate used for clamping the bracket of FIG. 1 to the wall surface;

FIG. 1b shows a typical shim used for leveling or normalizing the bracket against the wall to which it is mounted;

FIG. 2 is a perspective view of the wall bracket of FIG. 1 as it appears mounted to a wall surface;

FIG. 3 is a fragmentary perspective view of a building,

showing portions of a concrete floor and wall, with mounting studs already mounted in the wall at approximately, but not exactly the locations desired;

FIG. 4 is a front elevational view of a pair of restaurant tables mounted to a wall surface similar to that illustrated in FIG. 3, on mis-aligned mounting studs; and

FIG. 5 is a side elevational view showing the wall and floor in section, and revealing the manner in which the shimming wedges can be employed in cooperation with the bracket of the invention to achieve leveling and normalizing of the bracket prior to mounting of the table thereon.

In FIGS. 1 and 2, the numeral 10 is used to indicate the entire wall bracket assembly taken collectively, while a typical restaurant tabletop, mounted on bracket 10 is designated in FIGS. 4 and 5 by the numeral 11.

FIGS. 1 and 2 reveal that the principal part of bracket 10 is a heavy welded steel structure in the form of a right angle, and designated herein as bracket structure 12, which is seen to be comprised, in the preferred form, of a vertically disposed frame 13 and horizontally projecting horizontal support 14, the two being welded together to form an integral unit at 15, 16 and 17. A convenient and preferred construction for the horizontal support 14 is an inverted channel member, as illustrated, with several mounting holes 20, so that any of a variety of tabletops may be mounted to it.

The vertically extended frame 13 of bracket structure 12 is formed of upper and lower vertical plates 21 and 22, which are integrally connected, usually by welding, to a pair of vertical side members 23 and 24. The steel bars from which the members 21 to 24 are constructed are relatively thick and massive, and permit only negligible deflection under the stresses ordinarily encountered in the application for which this bracket is intended.

The vertical dimension of frame 13 is practically determined by the customary elevation of a restaurant table from floor level. It should be noted, however, that one of the secondary advantages of the present invention is that the brackets may make contact with the wall surface at points of maximum vertical spacing, through plates 21 and 22, regardless of the usual vertical location of the mounting bolts. Table-mounting brackets of the past were much more restricted than the present bracket in two respects: First, the total area of wall surface that could be contacted was limited, since if it were too extensive, and imperfections in the plane of the wall were picked up by having extensive contact, there was no suitable way for adjusting the bracket to normal and level position; secondly, bracket structures of the past were usually confined to some degree to the best placement of mounting bolt holes in the brackets, whereas the bracket of the present invention eliminates the bolt hole from the bracket structure 12, entirely.

The fragmentary perspective view of FIG. 3 shows the appearance of a typical floor and wall of poured concrete, with a series of upper and lower mounting studs, 31 and 32, respectively, seen projecting from wall surface 30 at a carefully spaced table-mounting distance above the surface of floor 33.

FIGS. 2 and 4 are perspective and front elevational views, respectively, of the bracket 10 as mounted, a single bracket 10 prior to attachment of the table top being shown in FIG. 2, and two brackets 10 side by side with tabletops 11 mounted thereon being seen in FIG. 4.

The bracket 10 is clamped to the wall surface 30 by upper and lower bolt plates 41 and 42, which have centrally located bolt holes 41a and 42a, to receive the threaded ends of mounting studs 31 and 32, respectively. In FIG. 2, fastening nuts 43 and 44 are seen in place.

The bars 41 and 42 are heavy enough to provide rigid attachment, regardless of shifting of the bracket 10 to any of the many locations in which it can be mounted with an upper and lower mounting stud 31 and 32 accommodated within the central opening 13a of frame 13.

To permit such shifting, the horizontal length of bars 41 and 42 is preferably a little over twice the horizontal width of frame opening 13a.

FIG. 1b shows a typical wedge or shim 50 which is used, wherever necessary, between one or both of the wall plates 21 and 22, to normalize and level the bracket 10. In FIG. 2, two such shims, 50a and 50b are shown in place between the surface of wall 30, and wall plates 21 and 22, respectively, for the respective purposes of normalizing and leveling. The term "normalizing" is used herein to name the procedure of adjusting bracket 10, in a horizontal plane, so that support member 12 projects from the ideal plane of wall 30 at a perfect right angle.

The bracket installation of FIG. 2 would be used in a case in which the surface of wall 30 behind vertical member 23 is defective in that it deviates rearwardly of the ideal wall plane. Correction for this imperfection is achieved by inserting shim 50a back of plate 21, so that support member 12 projects normally outward from the ideal plane of wall surface 30.

FIG. 2 also shows how shim 50b would be inserted back of lower wall plate 22 to raise the outer end of support member 12 to level position. FIG. 5 shows a shim 50c introduced between wall surface 30 and upper plate 21 in order to lower the support member 12 (and a tabletop 11 thereon) at the outer end. The dashed outline 11a shows the up-tilted position of table top 11 prior to adjustment with shim 50c.

FIGS. 3 and 4 illustrate that mounting studs 31 and 32 do not fall exactly at the locations called for by the architect's specifications. For example, as seen in FIG. 3, wall 30 may be partly or entirely of poured concrete 30a; and/or partly or entirely of masonry block joined by cement seams as indicated at 30b. Horizontal spacing specifications are indicated by the vertical center lines 34, while vertical spacing specifications are indicated by horizontal center lines 35 and 36. However, as illustrated in the front elevational view of FIG. 4, these many random deviations of the mounting studs 31 and 32 from the prescribed horizontal and vertical specifications are not reflected in the row of wall-mounted restaurant tables 11. With the bracket 10 of the present invention, adjustments are readily made to place the tables 11 at perfect elevation and perfect horizontal spacing, as shown in FIG. 4.

It will be understood that any suitable type of wall mounting stud may be employed, and also that it might be desirable to use more than two of said mounting studs 31 and 32 for mounting each single bracket 10. Thus, in the cross-sectional view of wall 30, a typical mounting stud, shown for purposes of illustration and not of restriction, is similar to an ordinary foundation bolt, with a down-turned end 31a imbedded in the concrete, or the mortar between concrete blocks, in wall 30. The outward projecting end 31b is threaded with standard bolt threads to accommodate nuts 43 and 44. In a typical application, only two large size bolts, one upper bolt 31 and one lower bolt 32, are required for mounting a typical restaurant table. However, it is one advantage of the present invention that, one could use 3, 4, or even more mounting studs in the wall, without requiring any great precision of placement, for the mounting of a standard bracket 10. For example, such a situation might be encountered in mounting two studs within a lath and plaster wall. Obviously, in such a case, additional bolt plates, such as bolt plates 41 and 42 would be required, one for each mounting stud.

It will be seen that bracket 10 of the invention is held in position by the pressure of bolt plates 41 and 42, only. The bolt plates 41 and 42 are situated outboard of wall surface 30 and frame 13, and are not attached to frame 13 in any way. Thus, a workman may install all of the brackets 10 in the long row of restaurant tables with nuts 43 and 44 only loosely tightened. He may then proceed up and down the line of brackets 10, with hammer and level, and a supply of shims 50, tapping each of the

brackets 10 into position. After the entire line of restaurant table brackets 10 are precisely positioned, normalized, and leveled, the nuts 43 and 44 will be tightened into position. Tabletops 11 may then be mounted, usually with almost no further adjustments, and booth seats precut to fit specifications, may be installed without requiring any special modification.

I claim:

1. An alignable wall bracket for use in mounting a table surface on a wall, in an application requiring that said table surface be level, that it be located at a predetermined vertical plane, and that its location meet predetermined vertical and horizontal alignment specifications when mounted on a plurality of mounting studs in said wall, and in which said wall surface has irregular and substantial departures from said vertical plane, and the location thereon at which mounting is desired, said bracket being comprised of:

a wall frame comprised of upper and lower wall plates, and a pair of vertical side members, said wall plates and side members being integrally attached to one another around a central opening, said central opening having a space sufficient to accommodate said mounting studs, when said mounting studs are at maximum allowable departure from said predetermined specifications, but with said frame being disposed to meet said specifications, and said upper and lower wall plates having vertical surfaces adapted to be located at said vertical plane of desired wall mounting;

a table support member integral with said wall frame and projecting horizontally therefrom for attachment of said table surface at the desired level;

a plurality of rigid retaining members adapted to be received on said mounting studs, said retaining members being located outboard of said vertical side members relative to said wall, said retaining mem-

bers extending laterally of said central openings to engage the outboard surfaces of said vertical side members, while accommodating limited adjustment of location of said wall frame to said wall surface; shim means for placement between said wall surface and said upper and lower wall plates to bring said bracket into conformance with said vertical plane of desired mounting and said leveling and alignment specifications; and

fastener means for attaching said retaining members to said mounting studs.

2. A wall bracket as described in claim 1 in an application in which said wall is comprised of masonry blocks joined by cement seams, and said mounting studs consist of two threaded bolts projecting from said wall at said seams near but not at said alignment specifications, said bolts being located one above the other near a common vertical alignment axis, and in which said bracket has said vertical members spaced horizontally to span adjacent vertical seams, and said upper and lower plates are spaced vertically away from said mounting studs by at least the spacing of horizontal seams in said wall, and each of said retaining members is a horizontal bar centrally bored to be received on one of said mounting studs, each of said horizontal bars having a horizontal length at least twice the spacing between said vertical side members.
